Primary Examiner — Darcey E Gottschalk

(57) **CLAIM**

The ornamental design for a packaging container, as shown and described.

DESCRIPTION

1. Packaging container

1.1 : Perspective

1.2 : Perspective

1.3 : Back

1.4 : Front

1.5 : Right

1.6 : Left

1.7 : Top

1.8 : Bottom

1 Claim, 8 Drawing Sheets
